UNITED STATES PATENT OFFICE

110,827

DESIGN FOR A COFFEEPOT

Frank Spina, New Kensington, Pa.

Application May 13, 1938, Serial No. 77,177

Term of patent 3½ years

To all whom it may concern:

Be it known that I, Frank Spina, a citizen of the United States, residing in New Kensington, in the county of Westmoreland and State of Pennsylvania, have invented a new, original, and ornamental Design for a Coffeepot, of which the following is a specification, reference being had to the accompanying drawing, forming a part thereof, wherein

I claim:

The ornamental design for a coffeepot, as shown,

FRANK SPINA.
